UNITED STATES PATENT OFFICE.

ERWIN A. GEIGER, OF RIDGEWOOD, NEW JERSEY; AUGUST F. SCHRAEGLE, OF RIDGEWOOD, AND HENRY T. JENNINGS, OF GLENDALE, NEW YORK, ASSIGNORS TO RAPID ADDRESSING MACHINE COMPANY, A CORPORATION OF NEW YORK.

ADDRESSING MACHINE.

Application filed September 22, 1925. Serial No. 57,867.

This invention relates to machines for printing a series of names and addresses or other lists of names or legends from sets of stencil cards or other address bearing strips, 5 and is more particularly designed to produce a machine in which the names or addresses in a relatively short list may be automatically printed over and over again, in which such names or addresses may be printed at 10 predetermined varying distances on a continuous web of paper and said web cut into sections of varying lengths, each containing one name or address or other printed legend, and in which a plurality of sets of such 15 printed strips or sheets may be simultaneously run off.

The invention is particularly designed to supply the requirements of the post office service in the printing of numerous sets of 20 tickets and labels to be used on mail bags and packages of mail matter to be consecutively delivered at the series of stations constituting a mail route. In the case of the 25 railway mail service from New York, for instance, there are scores of mail routes fixed by departmental practice, each route comprising from a dozen to a hundred or more stations. The mail clerks must put the first 30 class mail matter for each station along such a particular route in a separate mail bag or bags each of which must be labeled with the name of that station, and other mail matter for that station is put into packages each 35 of which must be similarly labeled. Each mail bag is so labeled by sliding a short slip of paper on which the name of the station has been printed into a suitable metallic frame fast on the bag, and longer sheets of paper having the station name printed 40 thereon are used for labeling the bundles of second class or other matter not put in the mail bags. This requires the New York office to print up 20 or 100 sets at a time of the tickets and labels for each route, and 45 this necessitates the running of a set of stencil cards or other printing devices each adapted to print the name of one station on the route through an inking and impression mechanism many times in succession. When 50 the list is short and the machine speeded up to the limit the set of cards will come through in a few seconds and the machine must then stand idle for a much longer time while an attendant is collecting and restack-

ing the cards so as to run them through again. To accomplish this automatically so that there may be no stoppage until the desired number of sets of tickets for that route have been printed the present invention employs an automatic restacking mechanism by which each stencil card of a set representing a given route, after passing through the printing mechanism, is automatically returned to the original card holding magazine, from which it will be again fed in its turn to the printing mechanism, and so on indefinitely until the desired number of sets of tickets or labels for that route have been printed. The machine hereinafter described is set up to print the successive 55 names or other legends on webs of paper which are then cut into sections and the amount of feed given the paper between each printing operation may be varied so that short tickets, long labels or other printed 60 forms may be produced at will. Also any web or strip of paper being printed is fed crossways of the line of travel of the stencil cards which are advancing along the guides from magazine to printing mechanism, so 65 that two or more sets of inking and paper feeding mechanism may be placed one behind the other along the path of the stencil cards, and, as a result, two or more tickets or labels printed at each cycle of operation 70 of the machine, each name or other legend being printed successively on two or more webs of paper. Obviously this doubles or trebles or otherwise multiplies the output 75 of the machine. Also, in order to enable the 80 machine to be used in the ordinary way and then discharge into another receptacle each stencil card which has passed through the printing mechanism, the card disposing mechanism is made convertible, so that the 85 cards may either be lifted up and carried back to be restacked in the feed magazine for automatic repetition of the printing 90 operations therefrom, or they may be discharged downward into another receptacle 95 in the usual way. Various other improvements in details of mechanism are involved 100 which will be hereinafter pointed out and illustrated in the accompanying ten sheets of drawing which show one form of commercial apparatus now in use by the United States Post Office and embodying the present 105 invention. In said drawings,

Fig. 1 is a front elevation of the main portion of the machine with parts removed and others broken away.

Fig. 1^a is a general side elevation of the entire machine with some small details omitted.

Fig. 2 is a general plan view with parts broken away and others shown in sections taken on different horizontal planes.

10 Fig. 3 is a detail side elevation on an enlarged scale showing a part of the card restacking mechanism with some parts shown in section and others broken away.

15 Fig. 4 is a similar detail side elevation showing the printing mechanism.

Fig. 5 is a detail front elevation on an enlarged scale showing the paper cutting, packing and intermittently acting feed mechanism, parts being shown in vertical 20 section.

Fig. 6 is a detail vertical cross section of the same mechanism taken on line 6—6 of Fig. 5 with parts broken away.

25 Fig. 7 is a similar section of the same mechanism taken on line 7—7 of Fig. 5.

Fig. 8 is a detail elevation of the paper feed locking device, looking from the left hand side of Fig. 5.

30 Fig. 9 is an enlarged detail front elevation of a part of the card handling device, showing the same in adjustment for the restacking operation.

35 Fig. 10 is a similar view showing certain of the parts in adjustment for ordinary stacking of the used cards in a receiving chute.

Fig. 11 is a similar view of another portion of the card handling device showing its connection with the card magazine, and

40 Fig. 12 is an enlarged detail sectional view of the paper feed locking device taken on line 12—12 of Fig. 8.

Fig. 13 is a perspective detail view of the clutch on the main driving shaft.

45 Throughout the drawings like reference characters indicate like parts.

1 represents the main frame of the machine at one end of which is the usual magazine 2 for stencil cards, the bottom card in 50 the magazine being pushed out along horizontal guides 3 (Figs. 1, 4, 9 and 10) through a printing mechanism and then discharged into a card disposal apparatus 5 (Figs. 1 and 9) at the other end of said guides.

55 A feature of this machine is that it prints twice from each card, thereby producing duplicate sets of tickets, labels or other printed reproductions of the name, or address or other legend borne by each card.

60 Accordingly two stencil cards 4, 4^a (Fig. 2) are shown in printing position. There is a long printing platen 6 (Figs. 1 and 4) which overhangs both cards which are in printing position and is supported on the 65 horizontal arm of a bell crank frame 7

through the medium of loose ball-bearing 8 and adjusting screws 9, 9, by which the platen 6 may be accurately aligned longitudinally so as to press evenly upon both cards, but left free to tip laterally on an axis determined by said adjusting screws. The bell-crank frame is pivoted on a horizontal shaft 10, (Figs. 3 and 4) journaled in the frame 1 and, at the end of its depending arm, carries the cam roller 27 which is held in contact with cam 28, carried on main driving shaft 19, by means of the tension spring 25, the other end of which is fastened to the main frame by hook 26.

The inking device cooperating with the platen 6 and stencil cards, 4, 4^a, and, together therewith, forming the printing mechanism, consists of two inking rollers 11, 11^a reciprocated along cam grooves 12 (Fig. 4) by reciprocation of the yoke 13 in which the rollers are journaled. This yoke is reciprocated by means of the bell-crank 15 to which it is pivoted at 14. Said bell-crank is pivoted to the main frame on an eccentric bearing 16^a carried on shaft 16, which is circumferentially adjustable to adjust the zone of travel of the inking rollers. This bearing may be clamped in any desired position by hexagonal nut 16^b (see Fig. 4). Bell-crank 15 carries on its other and shorter arm a roller 17 which is held in engagement with the cam 18 on shaft 19 by means of tension spring 29 connected to the bell-crank 15 at one end and to the main frame at the other end by hook 30.

100 Ink is applied to the rollers 11, 11^a by doctor rolls 24, 24^a (Fig. 4) running in ink fountain 21 and driven by gearing 20 from main shaft 19 as best shown in Fig. 4. Said doctor rolls are also geared to the inking rollers 11, 11^a by gear wheel 20^a when the platen 6 is raised and the inking rollers are lowered into contact with the doctor rolls and then caused to rotate in contact therewith by gear 20^a and pinion 20^b which have V-shaped teeth to facilitate engagement when the inking rolls are in position shown in Fig. 4. 22 is the usual adjustable knife for regulating the thickness of the film of ink on the doctor rolls, said knife being adjustable toward and from said roller by means of set screws 23.

110 The mechanism for feeding the stencil cards intermittently from magazine 2 along guides 3 to the printing mechanism comprises the reciprocating claw 31 (Figs. 1 and 11) pivoted at 32 on a slide 33 reciprocated by link 34 pivoted to the upper end of lever 35 which is pivoted to the main frame at its lower end 36 and vibrated by adjustable connecting rod 37 from crank 38 on short shaft 39 which is driven from the main shaft 19 by bevel gearing 40, 41 (Figs. 1 and 2). Claw 31 catches the inside of the pasteboard frame of the lowermost card 4

in the magazine 2 and the rear edge of the card is held up slightly by fingers 2^a (Fig. 11) which are adjusted by set screws 2^b, passing through slots in the wall of the magazine 2. To ensure easy entrance of the cards into guides 3, the lower edges of the guides are beveled as shown at 3^c, and a roller 3^a is loosely journaled in vertically slotted bearings 3^b to accommodate slight variations in thickness of the cards.

An important feature of the present invention consists in means for either returning each card, which has passed through the inking and impression mechanism, to the card magazine 2, or depositing it in a card collector from which all the cards of a given set or run may be removed after they have been collected therein and either filed away for storage or returned to the magazine 2 in a body to be used over again. This mechanism is illustrated in Figs. 1, 1^a, 2, 3, 9, 10 and 11, in which 50 represents generally a vibrating card disposal member mounted in the general card disposal apparatus 5. The details of construction of this member 50 comprise a horizontal plate 51 located above the inner end of a downwardly and outwardly extending curved chute 52 (Figs. 1^a, 3 and 10) into which the used cards may be forced by a downward movement of the plate 51 when said movement is properly timed and extends through a path the upper end of which is just above the level of the card guides 3, as indicated in Fig. 10. 52^b is a spring clip for holding the cards in the chute and preventing the top card springing back after the pressure of plate 51 is removed. This chute 52 may have a friction device therein adapted to be forced along the chute by the accumulating body of used cards deposited therein and so retain said cards in contact one with another in a column or bunch as also indicated in Fig. 10. As shown, this friction device comprises a movable body 53 which may be made in the form of a dumb-bell having a central passageway axially thereof in which are mounted two round-headed plungers 54 having limited movement in the passageway controlled by radial pins 55 moving in bayonet slots 56 in the side of body 53, said plungers 54 being normally forced outward by spiral springs 57 so that they make frictional contact with the side walls of the chute 52. As a result, each time another card is forced down into the chute by the downward movement of plate 51 the dumb-bell 53 rolls slightly along the chute to allow the other cards to move along the chute a distance equal to the thickness of the card so added to the collection. A card filing tray 52^a may be placed in chute 52 as shown in Fig. 1^a. The dumb-bell 53 would then precede the cards in this tray.

The plate 51 is supported and offset from a slide or carriage 58 which moves on vertical guide rods 60 under control of the forked lever 61 (Figs. 1 and 3) engaging the anti-friction roller 59 carried on slide 58. 70 Forked lever 61 is pivoted on the main frame at 62 and vibrated by cam roller 63 engaging one or the other of the cam grooves 64^a or 64^b cut in opposite faces of the disc 64 which is keyed to main shaft 19. 75 The two cam grooves are set substantially 180 degrees apart as indicated in Fig. 3 and when the disc 64 is set on the shaft 19 with one groove engaging cam roller 63 the card disposal member 50 reciprocates as previously described through a zone extending from a point slightly above the level of the card guides 3 down to the position shown in broken lines in Fig. 10, and packs the used cards into chute 52 as there shown. 80

If it is desired to return the used cards immediately to the magazine 2 instead of packing them in chute 52 as above described the cam disc 64 is reversed on shaft 19 and consequently the cam roller 63 engages the groove in the opposite side of said cam discs and the path of travel of the card disposal member 50 is changed so that it reciprocates in a zone extending from a point just below the end of card guides 3, as shown in Fig. 9, to an elevated position there shown in broken lines. Each card delivered from the guides 3 is then received upon an inclined table 65 pivoted to the card disposal member at 66 and normally tipped up in the position shown in full lines in Figs. 1 and 9 by spring 67, further tipping of the table being prevented by stop 68. A spring lock 69 may engage table 65 to hold it in a more nearly horizontal position as indicated in Fig. 10. While table 65 is in the normal position shown in Fig. 9 and is lifted intermittently to the position there shown in broken lines, the card 4^b carried thereby is prevented from sliding off from it by the vertical guide 65^a. Consequently the card remains in such position on said table that its upper edge comes in contact with the upper pair of transfer belts 70 which are endless and travel around pulleys 71 on shaft 72 and pulleys 83 mounted in the other end of belt carrying frame 95 (Figs. 1 and 11). Said frame 95 is pivoted at its right hand end on shaft 72 which is journaled in brackets 73 (Fig. 2) and said frame 95 is supported at its left hand end by lugs 85 having a vertical adjustment on vertical rods 86 and held in any position of adjustment thereon by set screws 87. A lower set of traveling endless belts 80 running over pulleys 81 and 84, are also carried by frame 95. Tension rollers 94, 94 are set in this frame cooperating with belts 70 and 80 as shown in Fig. 1. The lower belt 80 is driven by the train of spur gears 79 from shaft 72 of pulley 71. Shaft 72 has on its outer end 110 115 120 125 130 135 140 145 150 155 160 165 170 175 180 185 190 195 200

bevel gear 74 (Figs. 2 and 3) meshing with bevel gear 75 on vertical driving shaft 76, to which motion is given by electric motor 78 through bevel gearing 77.

5 As soon as the card carried by table 65 comes in contact with belt 70 which runs substantially parallel to said table, said card is slid upward off the table by friction of said belt, against which the card is forced by a 10 slight compression of spring 67 (Fig. 9). These belts are usually made of a composition containing rubber, and the card is drawn in between the adjacent strands of belts 70 and 80 and by them carried up and 15 discharged into the magazine 2 as shown in Figs. 1 and 11. To make sure that the card is deposited in this magazine right side up, there is preferably added to the above described mechanism a pair of discharging 20 belts 90. These run over pulleys 89, 89, (Figs. 2 and 11) journaled in frame 95 adjacent to pulley 83, and over pulley 91 carried by arm 92 pivoted at its upper end on shaft 93 in frame 95. This short discharge 25 belt 90 is driven by spur gearing 82 (Figs. 1, 2, and 11) from the shaft of pulley 83. To facilitate the transfer of the cards from control of belts 70 and 80, the belts which are in close contact at the lower end as shown 30 in Fig. 1, are allowed to diverge slightly at the upper end as shown in Figs. 1 and 11. Also, to positively guide the card into the magazine 2, roller 96 is provided beneath belt 35 90 and so spaced away from pulley 84 that the front edge of each stencil card will pass over roller 96 before the rear edge of the card is released by belt 80. Roller 96 is carried by a vertically adjustable slide which is clamped to the magazine wall by set-screw 40 96^a at the desired height (Fig. 11).

The discharge end of this belt-conveyer system can be raised or lowered to accommodate stacks of cards of different heights in the magazine by shifting brackets 85, 85, up 45 or down on rods 86 after loosening set-screws 87, 87. If a set of 12 or 15 cards only are being used over and over again, the delivery belt system would be lowered so as to bring the lower portion of the discharge belt 90 slightly above the top of the stack in the magazine 2. If, on the other hand, a set of 50 or 100 cards were being used, the delivery 50 end of the belt system would be raised correspondingly. Roller 96 is also adjusted vertically, as above described, to maintain contact with belt 90.

When this transfer or restacking apparatus is not being used the discharge belt 90 may be swung up out of the magazine 2 by 55 swinging the arm 92 upward as shown in dotted lines in Fig. 11, the belt 90 being sufficiently elastic to allow of the resultant stretching required to permit of this operation. Of course when this restacking apparatus is not being used current is shut off

from motor 78. In such case the inclined table 65 is locked down by spring lock 69 in the position shown in Fig. 10, as the cam disc 64 is reversed to cause the plate 51 to come into operation as a means for packing the 70 cards downward into chute 52, instead of employing table 65 to lift them up and deliver them to the restacking mechanism last above described. This avoids wear on belt 70 which would otherwise possibly result from 75 table 65 knocking against the overhanging portion of said belt.

To facilitate the reversal of double-faced cam disc 64, the bearing 19^a for that end of shaft 19 is fastened to main frame 1 by a 80 set-screw 19^b (Fig. 3) and maintained in alignment by rib 19^c fitting in the base of the bearing pedestal.

The electric motor 78 (shown in Figs. 1, 1^a and 3) does not supply the power for running the entire machine but constitutes a 85 separate drive for the card stacking and restacking mechanism as previously described. The power for driving other portions of the machine is supplied from the larger electric 90 motor 109 (Figs. 1 and 1^a). This main motor 109 drives pulley 107 by means of belt 108 and smaller pulley 105, on the same counter-shaft 106 on which pulley 107 is mounted, drives pulley 100 on main shaft 19 through 95 belt 104.

The pulley 100 shown clearly in Fig. 2 is loosely mounted on shaft 19, said shaft being supported by the bearings 101 and 19^a. Projecting from the hub of the pulley 100 are 100 three pins 101^a equally spaced apart, which revolve with the pulley and act as the driving means when engagement is made with the clutch key 102^a. The clutch key 102^a is 105 slidably mounted in the clutch head 102 fixed to the shaft 19 and may be held out of the path of the revolving pins 101^a by means of a cam 102^b on the clutch rod 103. When clutch rod 103 is in raised position the clutch key 102^a is withdrawn and the pulley revolves idly on the shaft 19 but when it is in the lowered position as shown in Fig. 1, the clutch key is released under pressure, produced by coiled spring 102^c (see Fig. 13) and is immediately engaged by one of the 115 pins 101^a, which starts the machine in motion.

The clutch rod 103 may be operated in any convenient manner as by one or more clutch operating levers 103^a shown in Fig. 1^a, which are connected to the clutch rod 103 by any convenient apparatus not illustrated in the drawings.

Paper feeding apparatus.—As illustrated, this machine is arranged to print the addresses borne by the stencil cards upon two webs of paper, 111, 111^a, (Fig. 2) and these webs or ribbons of paper are preferably supplied from separate rolls mounted on the shaft 42 (see Fig. 1^a) one of which rolls is 120

shown at 110. The paper is gradually unwound from the roll by tension of the continuously operating feed rollers 128 and 129, the former of which is journaled in the lower end of swinging radius-frame 130, the upper end of said frame being pivoted on the shaft 131, and the upper feed roller 128 being driven positively by chain and sprocket mechanism 132 from the main shaft 19. After leaving the continuously operating feed rolls 128, 129, each web of paper is allowed to hang in a loop and then pass back over the paper roll 110 from which it came, and under a guide roller 112, on to the table 43. Roll 112 is lightly held in its journals by two springs, one of which is shown at 113 (Fig. 1^a, 3 and 4) so that it may be conveniently removed, and also to provide a tension release on the paper if the sudden pull of the intermittent paper feeding mechanism hereinafter to be described subjects the paper web to an excess of tension which must be relieved to prevent rupture.

On the table 43 are laterally adjustable paper guides 115 which may be adjusted on the table by movement relative to the holding screws 125 which pass through said guides and are seated in horizontally extending slots 125^a (see Fig. 2). Consequently these guides can be adjusted accurately to paper webs of different widths and can also be adjusted accurately to deliver said webs to the printing mechanism in proper register with the stencil cards. 114, 114 are springs carried by the platen arm 7 and bearing upon the paper webs 111, 111^a to produce slight frictional contact therewith, which is greatest when the platen 9 is lowered into printing position, thus insuring the paper being firmly held at the instant it is being printed.

After passing through the printing mechanism the paper webs pass under the guide bar 116 (Figs. 1^a, 2, 6 and 7) which may be rotatable and then up over the guide pulleys 118 (see Figs. 6 and 7) and down again between the intermittently actuated feed wheels 119 and 120, thence under the guide plate 189, held in position over the stationary knife edge 188 by screws 189, and under the swinging knife blades 184, 184^a (see Figs. 5, 6, and 7).

The sections of paper, each bearing a stenilized address or post office station name or other legend, cut off by these knives drop into the chute 190 (Figs. 1^a and 7) and are positively packed down into said chute against sliding holder 194 (Fig. 7) by a packer head 168 which is vertically reciprocated by means of mechanism hereinafter to be described.

It is obviously essential that the feed wheels 119, 120, or other feeding mechanism, which is to pull the web of paper through

the printing mechanism, must be intermittent in action in order to allow the paper to be at rest during the printing operation. The particular train of mechanism herein illustrated as transmitting motion to produce this intermittent feeding action may be traced from the main shaft 19 to the shaft 126, which carries the driven feed wheels 119, as follows:

Helical gearing 133 (Fig. 2) transmits motion from shaft 19 to counter-shaft 134, carrying spur gear 135, meshing with gear 136 carried by a second counter-shaft 137 (Figs. 1 and 4). This second counter-shaft 137 projects out through the front of the main frame 1 of the machine as shown in Fig. 6 and is there coupled to a third shaft 139 carried by the swinging frame 117, said frame 117 being hinged to the main frame 1 at 191 (Fig. 2) so as to permit it to be swung outwardly in a horizontal plane when the retaining bolt 117^a (see Fig. 6) is removed and the shaft coupling 138 (Fig. 6) broken. This coupling between shaft 137 and 139 is a muff coupling, the ends of the shafts being cut away so as to intermesh one with the other and then be held in engagement by the sleeve member 138 when it is in the position shown in Fig. 6. The spring-pressed ball 138^a engaging either the groove 138^c or 138^b in shaft 139, holds said sleeve 138 in coupled or uncoupled position. When the coupling is to be disengaged preparatory to swinging the frame 117 to one side, the clutch sleeve member 138 is slid to the left until the spring-pressed ball 138^a drops into the groove 138^b. This opens the coupling and holds it open.

The constant rotation of shaft 139 when coupled to shaft 137 is transmitted by helical gearing 141 (Figs. 5 and 6) to the knife operating shaft 142 which shaft also carries a crank disc 142^a having a crank pin 143. On this is carried the slipper block 144 sliding in slot 145 in the toothed sector 146 pivoted at 147 to swinging frame 117. The toothed sector 146 which is thus vibrated by rotation of the crank disc 142^a meshes with gear 148 loose on short shaft 126^a journaled in the gear box 153 which box is supported from frame 117 by studs 153^a (Figs. 2 and 5). This gear 148 turns loosely upon shaft 126^a but transmits motion to it at different rates of speed according to whether it drives the gear wheel 152 (which is splined on shaft 126^a) directly through engagement of the clutch members 158, or indirectly through gears 149 and 151 which are fast on a short shaft 150. The described gearing mechanism corresponds to the back gear of a lathe. The gear 152 slides longitudinally on the shaft 126^a, being carried by sleeve 154 which may be grasped by the knurled flange 157. The spring-pressed ball 156 engaging one or the other of the circumferential grooves

155 in sleeve 154 holds the gear 152 either in its inward position of adjustment so that it is directly clutched to gear 148 and out of mesh with gear 151, or in its outward position so that it is free from clutch engagement with 148 and then in mesh with gear 151, in the position shown in Fig. 2. On the inner end of short shaft 126^a is carried the crank 159 on the outer end of which is mounted the pawl 160 held in yielding engagement by spring 161 with ratchet wheel 162, which latter is fast on the end of shaft 126, which carries the feed wheels 119.

By operation of the mechanism in gear case 153 the constant rotation of the shaft 142 is transformed into a vibratory movement of the pawl 160 of greater or less amplitude according to the position of the gear 152, and this vibratory movement is transformed by the pawl and ratchet mechanism into an intermittent, one-way rotation of the shaft 126 and feed wheels 119 of greater or less extent.

The upper feed wheels 120 Figs. 2 and 5) cooperate with the intermittently driven feed wheels 119 as spring-pressed idlers, being mounted on shaft 121 journaled in vertically sliding blocks 122 which are forced downward by springs 123 (Fig. 6). To lift idler wheels 120 from contact with the paper supported by driven wheels 119, the cam plates 124 mounted on shaft 121 are turned by handle 124^a in a counter-clockwise direction, (looking at Fig. 7). This causes the full face 124^a of the cam plate to ride on stationary pin 124^b and slightly lift shaft 121 and wheel 120. Projections 124^c on cam plates 124 limit their rotation in either direction.

To prevent feed wheels 119 from overrunning the pawl and ratchet gear 160, 162 which intermittently actuates them, and to insure the accuracy of the paper feed, the intermittently acting locking apparatus illustrated in Figs. 8 and 12, and partly shown in Figs. 2 and 5, is provided on the other end of shaft 126. This consists of two notched discs 171 and 172 keyed to shaft 126 and co-acting with a spring-pressed finger 173 carried by eccentric pitman 174 which is reciprocated by eccentric 179 on shaft 142, being guided by shaft 126 which passes through slot 178 in said pitman. Finger 173 can be pushed inward or pulled outward by grasping knob 175, and is held in one or the other position by pin 176 pressed downward by spring 177. This pin 176 is screwed into a saddle piece 173^a which has a certain amount of up-and-down play in the recess in pitman 174 in which it is located, when spring 177 is compressed,—pin 176 and saddle piece 173^a moving together. If finger 173 is moved inwardly or outwardly by means of knob 175 pin 176 and saddle 173^a are both thereby lifted slightly

as the nose of the pin rides into or out of the recesses 175^a in the short endwise sliding shaft carrying finger 173. The outer disc 171, as shown, has three equi-spaced notches with which finger 173 may co-act, thus allowing shaft 126 after finger 173 has been withdrawn from any one notch, to make a third of a revolution before it is locked by finger 173 dropping into another notch. Inner disc 172 has fifteen notches, so that when finger 173 is pushed inward and left in position to cooperate with disc 172, shaft 126 can make only one fifteenth of a revolution before it is locked by finger 173 dropping into another notch. As a result, when finger 173 is pushed inwardly wheels 119 will feed lengths of paper webs 111, 111^a through the machine of only one fifth the length they would feed if finger 173 were pulled outwardly and co-acted with notched disc 171. The constantly rotating shaft 142 and eccentric 179 continuously reciprocate pitman 174, lifting finger 173 from engagement with any notch in discs 171 or 172 at or before the beginning of each feeding stroke of pawl 160, and then moving finger 173 down again quickly enough to press it against the particular disc with which it is co-acting before the feed motion of pawl 160 is completed, so that finger 173 may snap into the next notch as soon as it comes into register. If sliding gear 152 (Fig. 2) is clutched directly to gear 148 so as to feed a long section of paper through the machine at each printing cycle, finger 173 should be placed in the plane of disc 171. If sliding gear 152 is in mesh with gear 151 so that only short sections of paper are being fed through the machine, finger 173 should then be pushed into the plane of disc 172. In either case, if the pitman 174 is pulled down before the next notch in the co-acting disc has come under finger 173, spring 177 will yield and prevent breakage of the parts, and yet snap the finger into the notch as soon as it does reach the proper position.

Paper cutting mechanism.—The webs 111, 111^a of paper are cut into sections according to the length fed out by the last above described mechanism, and this is done by the scissors-like action of swinging knives 184, 184^a (Fig. 5) on the stationary knife 188 (Fig. 7). Knives 184, 184^a are pivoted at 185, 185 to frame 117 and are oscillated up and down by eccentrics 181 (Fig. 7) on shaft 142 through eccentric rods 182 connected to the knives by universal joints 183 at the upper ends of said rods. The knives 184, 184^a have projecting lugs 195, 195^a, at their heels which are always in contact with fixed knife edge 188 and so ensure proper scissors-like action of the knives, under action of springs 186 (Fig. 6).

Packer mechanism.—The packer bar and T-heads 168 (Figs. 5 and 7) previously de-

scribed are vertically reciprocated in guide slots 170 by cam discs 165 on shaft 164, the cam rollers 166 on the lower ends of rods 167 meshing with the cam grooves in discs 165, and the upper ends of said rods being fastened by screws 169 to the ends of the packer bar which slide in the before mentioned vertical slots 170 formed in brackets 187 (Fig. 6) carried by frame 117. Shaft 164 is driven by chain and sprocket gearing 163 (Figs. 5 and 7) from shaft 142 and at the same speed. To adjust the zone of movement of the packer heads the rods 167 may be made adjustable in length. As shown, each rod is made in two sections which are joined together by a turn-buckle 196.

The paper feeding, cutting and packing mechanism above described are so timed that while knives 184 and packer bar 168 are raised, feed wheels 119 are rotated the predetermined fraction of a revolution to feed printed sections of paper webs 111 and 111^a under the knives and packer bar. Then, while the feed wheels are at rest and pawl 160 (Fig. 6) is moving to the right, the knives 184, 184^a are pulled down to cut off the said printed sections of paper webs, and are followed by the packer bar 168 and T-heads which push the cut-off sections down into chutes 190 against friction support 194, and under springs 192 where the printed tickets or labels collect in a stack as shown at 193 in Figs. 1^a, 6 and 7.

The manner of use of the invention may be briefly described as follows:

If it is desired to print up say one hundred sets of mail bag tickets for a route having ninety-one stations, the set of ninety-one stencil cards bearing the names and other data necessary to be printed on the tickets are stacked in the magazine 2, the short discharge belt 90 being swung up into the dotted line position indicated in Fig. 11 to permit this stack of cards to be inserted in the magazine. The upper end of the belt carrying frame 95 is then raised or lowered and clamped in position by set screws 87 so that when discharge belt 90 is turned back into normal position it will be supported slightly above the top of the stack of cards in the magazine as indicated in full lines in Fig. 11. The cam disc 64 is placed on its supporting shaft 19 so that the cam groove producing motion of the card elevator through the upper zone is brought into engagement with cam roller 63, gear 152 is placed in the position shown in Fig. 2 so as to reduce the amplitude of vibration of pawl 160, and locking finger 173 is pushed inward to cooperate with notched disc 172 which has the greater number of notches cut in its periphery.

The webs of paper 111, 111^a having been properly threaded through the machine and

a feed roller 128 of the proper diameter which will feed a short length of paper web during each cycle of operation just equal to the length of the desired ticket, having been installed, the clutch 101^a is thrown in and 70 the machine begins to operate.

The cards in magazine 2 are fed one by one to the impression and inking mechanism and the name or legend on each card is printed first upon paper web 111^a, and, at 75 the next cycle of operations, on paper web 111. While the printing platen is raised and the paper webs are free, the feed wheels 119 are given one fifteenth of a revolution by pawl 160, which is sufficient to pull portions of the paper webs through the printing mechanism equal in length to that of the desired ticket. The loop of paper hanging between the roll 110 and feed rollers 128, 129, affording the necessary slack for this 80 intermittent feeding action on the paper. The free ends of the printed paper webs are projected under the swinging knives 184, 184^a, at each feeding operation and, during the next printing operation, are cut 85 off and packed down into receiving chute 190 by the packer head 168, as previously described. The stroke of the packer head is so adjusted at slotted connection 196 that the stock of tickets 193 is forced downward 90 far enough to make sure that, on the up-stroke of the packer, the stack will not expand enough to raise its top above the edge of fixed knife 188.

While the printing platen is raised the 100 line of stencil cards in the guides 3 are fed forward by the pulling out of another card from the bottom of magazine 2 by claw 31 and the card which has just been used to print on web 111 is subsequently discharged 105 from the ends of guides 3 upon the inclined table 65 of the card elevator, which is then in the position shown in full lines in Fig. 9. While the next printing operation is being performed the card elevator rises into position shown in dotted lines in Fig. 9, the card carried by it is spring-pressed against the under sides of the upper feed belts 70, and, by the friction thereof, is pulled off the table drawn in between belts 70 and 80, and ultimately discharged between belt 90 and roller 96 on top of the stack of cards in the magazine 2.

The machine is thus allowed to run the set of ninety-one stencil cards through the inking and impression mechanism over and over again, printing successive sets of tickets, each containing the names of the ninety-one stations on the route, until the desired number of sets of such tickets are thus completed. A counting mechanism, not shown, may be installed on the machine, and if this has been done the attendant, when he sees that the number of printing operations thereby indicated equals or ex- 120 125 130

ceeds the total number of tickets which would be needed to complete the hundred sets, can open the clutch, stop the machine, withdraw that stock of cards from the magazine and remove the sets of printed tickets collected in the chute 190.

If labels are to be printed instead of short tickets a larger feed roller 128 is substituted in the continuously operating set of feed rollers 128, 129 the changing gear 152 is slid inward so as to free it from gear 151 and produce engagement of the direct drive clutch 158, and the locking finger 173 is pulled out in the position shown in Fig. 12 to cooperate with the notched disc 171 which has only 3 notches in its periphery. Then, when the machine is started up, a length of paper web five times as great as that before fed will be drawn through the printing mechanism at each operation and a correspondingly longer printed section will be cut off and packed into the chute 190. Otherwise, the operation is the same.

If a series of stencil cards are to be used too numerous to come within the scope of the restacking apparatus, or if for any reason only one set of tickets or labels or other documents are to be printed, the cam 64 is reversed with the result previously described, that is to say, the stencil cards are not restacked in magazine 2, but are packed down into chute 52 from which they must be removed by hand for storage or replacement in magazine 2 if additional sets of tickets or labels are to be printed from them. If the chute 52 is adapted to hold a card tray 52^a as shown in Fig. 1^a, the cards are packed in this, and when it is filled it is removed for storage with its contents, and an empty tray is placed in chute 52, for a continuance of the described operation.

While the impression platen is descending upon the paper webs, the printed ends of which are firmly held between the feed wheels 119, 120, the springs 114, 114, are pressed downward on the paper webs and given a slight backward drag thereon which makes certain that the paper will be stretched smoothly across and over the stencil cards at the moment the platen presses the paper down on the cards and while the inking rollers are traveling across the under faces of the latter.

While means for operating simultaneously on only two webs of paper are shown, obviously this number could be increased by further duplication of the apparatus shown.

Among the advantages of the invention may be mentioned the increased output of a single machine and attendant resulting from this last mentioned multiple feature. The automatic restacking operation which enables the machine to go on and do its work while the attendant is engaged in other work, and the variety of product obtainable from

a single machine as the result of the adjustable paper feed.

The adjustable card-supporting fingers 2^a are useful in ensuring the proper engagement of feed claw 31, when the cards are warped so as to have a slight convexity on their lower faces. Raising the rear edge of the card then enables its front edge to lie flat on the lower card guide in the line of travel of claw 31.

The special form of mechanism for feeding the webs of paper is particularly advantageous in its operation because, being driven by a crank, it begins to move gradually as the crank passes its dead center and gradually accelerates to a maximum and then gradually decreases to zero, during each cycle of feeding operation. As a result, the paper is subjected to the minimum strain by the pull of the feeding mechanism and the gradual decrease of speed at the end of each cycle decreases the liability to over feeding.

The main driving clutch, illustrated in Figs. 1 and 2, is advantageous in that the three-point engagement afforded by the pins 101^a enables the driving mechanism to pick up the driven mechanism quickly whenever the clutch is thrown into operation, and without waiting for the fly-wheel 100 to make nearly a full revolution before engagement occurs, as is sometimes the case with ordinary forms of clutches.

Having described the invention, we claim:

1. In an addressing machine comprising a magazine for address bearing strips, mechanism adapted to print addresses from such strips, and means for feeding such strips consecutively from said magazine through said mechanism, the combination, with the above described apparatus, of a restacking device adapted to automatically return each address bearing strip to said magazine immediately after such strip has passed through said printing mechanism.

2. In a printing apparatus comprising a magazine, a series of stencil cards stacked in said magazine, an inking and impression mechanism adapted to cooperate with said stencil cards to print the legends appearing thereon, and means for feeding said cards consecutively from the bottom of said magazine through said inking and impression mechanism, the combination, with the above described apparatus, of a device adapted to automatically convey each card after it is discharged from said inking and impression mechanism back to the top of the stack in said magazine.

3. A combination such as set forth in claim 1 in which said restacking device comprises a pair of cooperating traveling belts located over said printing mechanism and extending from the discharge end thereof back to said magazine.

4. A combination such as set forth in claim 1 in which said restacking device comprises a pair of cooperating traveling belts located over said printing mechanism and extending from the discharge end thereof back to said magazine, and means for adjusting the height of the delivery ends of said belts, whereby stacks of address bearing strips of various heights may be used.
5. A combination such as set forth in claim 1 in which said restacking device comprises a pair of traveling belts placed one over the other and located over said printing mechanism, the upper belt projecting beyond the lower one over the discharge end of said printing mechanism, and a reciprocating elevator adapted to receive each card discharged from said printing mechanism and lift it into contact with said upper belt.
6. In an addressing machine comprising a magazine adapted to hold a stack of address bearing strips, mechanism adapted to print the addresses from such strips, guides extending from the bottom of said magazine to and through said mechanism, and means for feeding such strips one by one from said magazine along said guides, the combination, with the above described apparatus, of a strip conveyor extending from a point over the discharge end of said guides back to said magazine, a receptacle for such address bearing strips below the discharge end of said guides, and a vertically reciprocating member adapted to either lift each strip discharged from said guides up to said conveyor, or to force it down into said receptacle, according to the timing and zone of its reciprocation.
7. In an addressing machine employing stencil cards and having a magazine in which a series of such cards may be stacked, the combination, with said magazine, of a card restacker comprising a pair of traveling belts located one over the other, the upper belt projecting beyond the lower one at the intake end of the conveyor, and the discharge end of the conveyor being adjustable vertically along an open side of said magazine, and means for forcing cards one at a time up against the projecting under surface of said upper belt, whereby each card is carried between said belts and projected into said magazine, at a predetermined height.
8. A structure such as set forth in claim 7 combined with a short traveling discharge belt extending from the upper end of the upper belt of the main conveyor into the card magazine.
9. A structure such as set forth in claim 7 combined with a short traveling discharge belt extending from the upper end of the upper belt of the main conveyor into the card magazine, and a guide roller mounted
- in the side of said magazine under said discharge belt and in contact therewith when no card is passing between the two.
10. A structure such as set forth in claim 7 combined with a short traveling discharge belt extending from the upper end of the upper belt of the main conveyor into the card magazine, and a guide roller mounted in the side of said magazine under said discharge belt and in contact therewith when no card is passing between the two, said discharge belt having its outer carrying pulley supported on a swinging arm pivoted above its inner carrying pulley, whereby said discharge belt may be swung upward and out of said magazine when not in operation.
11. In an addressing machine employing stencil cards as the address bearing elements, a convertible device for either packing such cards after use into a receptacle or restacking them in the machine for re-use, which said device comprises, in combination, a vertically reciprocating member, a double faced reversible cam disc, and motion conveying mechanism from said cam to said reciprocating mechanism, whereby when said mechanism engages one face of said cam disc the apparatus operates as a card restacker, but when the cam disc is reversed, the apparatus operates as a card packer.
12. In a card conveyor for addressing machines the combination of a pair of inclined endless traveling belts arranged one over the other with the end of the upper belt loop projecting beyond the lower belt at their lower ends, and a vertically reciprocating elevator located under said projecting belt, said elevator being provided with a spring supported carrier plate for cards so inclined as to be substantially parallel to the inclined portions of said belts.
13. A structure such as set forth in claim 12 combined with means for locking said carrier plate in a lowered position when contact with the belt is to be avoided during continued reciprocation of said elevator.
14. In an addressing machine comprising an inking and impression mechanism adapted to print from a series of address bearing strips, a platen for such impression mechanism having a loose universal joint mounting, and screws for adjusting said platen on said universal joint mounting in different planes, about the axis determined by said adjusting screws.
15. In a printing mechanism adapted to operate on a continuous web of paper, the combination of a guide bed for said paper, a platen, forming part of the printing mechanism, mounted over and capable of moving toward and from said bed, a feeding device adapted to draw the web of paper over said table and under said platen, and a spring pressure device moving with the platen and adapted to press the paper against said

table during the descent of the platen for each printing operation, said spring pressure device being located on the side of the platen opposite that on which said paper feeding mechanism is located, whereby said paper is placed under tension at the place of, and during, each printing operation.

16. A combination such as set forth in claim 15 in which said spring pressure device has a slight backward motion over the web of paper on its downward movement after making contact therewith.

17. In a printing mechanism adapted to print on a web of paper and to cut the same into sections, a paper feeding mechanism, comprising, in combination, a rotatable feed wheel, a reciprocating toothed sector having a uniform amplitude of reciprocation, a gear wheel meshing therewith, a pawl and ratchet mechanism having one element connected to said feed wheel, and change gearing conveying motion from said sector driven gear wheel to the other element of said pawl and ratchet mechanism, whereby when said change gearing varies the amplitude of motion transmitted from the uniform oscillations of said sector driven gear to the pawl and ratchet mechanism, different lengths of paper web are fed forward at each cycle of operation.

18. In an addressing machine adapted to print on a web of paper, an intermittently acting feed mechanism for said paper capable of adjustment as to amplitude of each feed motion, and a paper cutting mechanism operating once during each printing operation, whereby the addresses may be printed on sections of paper of different lengths.

19. In a printing apparatus adapted to operate on a web of paper and provided with adjustable means for feeding various lengths of paper through the printing mechanism comprising cooperating intermittently operating feed wheels mounted on parallel shafts, the combination, with said feed mechanism, of a plurality of differently notched discs rigidly mounted on one of said shafts, a cooperating spring pressed locking finger and means for withdrawing said finger from notch engagement or reengaging it by movement radially of the discs at each cycle of feeding operations, said finger being manually adjustable for engagement with the notches in one or another of said discs, whereby each motion of said paper feeding mechanism is positively limited to an amount corresponding to the angular spaces between successive notches in the particular disc with which said finger is in engagement.

20. In an addressing machine comprising printing mechanism, means for feeding a series of address bearing strips through said mechanism, means for supporting a roll of paper and guiding said paper to said print-

ing mechanism, a prime mover and a main frame in which the above recited elements are mounted, the combination, with the above described structure, of a horizontally swinging frame hinged to the front of said main frame and paper feeding mechanism carried thereby, together with a separable drive shaft, one section of which is journaled in said main frame and connected to said prime mover, while the other section thereof is journaled in said swinging frame and connected to said feed mechanism, and a separable coupling for said shaft sections, whereby the two above described groups of mechanism can be geared together when said swinging frame is in its inward position, or separated for examination and repair by swinging said frame outwardly.

21. In an addressing machine employing stencil cards and having a vertical magazine open at one side in which a series of such cards may be stacked, the combination with said machine, of a card restacker comprising a pair of traveling belts located one over the other and the discharge ends of said belts being adjacent to the open side of said magazine, a short discharge belt extending from the upper end of the upper belt of the first-mentioned pair and into the card magazine through said open side thereof, and a guide roller mounted on said magazine beneath said discharge belt.

22. A combination such as described in claim 21 in which the belts of the first mentioned pair are in contact at their intake ends but slightly separate at their discharge ends.

23. A combination such as described in claim 21 in which both the guide roller and the discharge belt are vertically adjustable to accommodate card stacks of different heights in the magazine.

24. In an addressing machine employing address bearing strips, the combination of a discharge chute for receiving such address bearing strips after they have been used in the machine, and a filing tray for such strips removably attached to the end of said chute in position to receive the strips discharged therethrough, and constituting an extension thereof.

25. A structure such as described in claim 24 combined with a spring clip mounted on one wall of said chute adapted to engage and retain in said chute the stack of address bearing strips delivered to it.

26. A combination such as described in claim 11 in which said cam disc is removably mounted upon a shaft and the end of said shaft nearest said cam disc has a journal bearing removably mounted on the main frame of the machine.

27. In an addressing machine adapted to print a series of addresses on a web of paper and cut the same into sections, the combina-

tion of a knife, a chute for receiving the cut sections of paper, a reciprocating packer head adapted to force said cut sections into a stack in said chute and means for adjusting the zone of movement of said packer head to allow for the expansion of the stack of paper strips during return stroke of the packer.

28. In an addressing machine adapted to print a series of addresses on a web of paper and cut the same into sections, the combination, with printing and cutting mechanism, of an intermittently operating mechanism for feeding the paper web which gradually accelerates from the state of rest to maximum speed at the middle of the feeding operation and then gradually decreases to zero at the end thereof.

29. A device for supporting a series of cards in a chute, which device comprises a roller adapted to extend lengthwise across said chute, combined with plungers mounted in the ends of said roller in line with its axis and elastically pressed outward to frictionally engage the side walls of said chute.

30. A combination such as described in claim 29 in which said plungers are provided with locking means for holding them temporarily with their outer ends withdrawn out of engagement with the said chute walls.

31. In an addressing machine comprising a vertical magazine for stencil cards or the like address bearing strips, card guideways leading from the bottom of said magazine and means for forcing the cards one by one from said magazine into said guideway, the combination, with said above described apparatus, of a guide roller located at the junction of the upper walls of said card guides and the adjacent wall of said magazine.

32. A combination such as described in claim 31 in which said roller is loosely journaled in vertically slotted bearings, whereby it may automatically adjust itself to cards of slightly varying thickness.

33. An apparatus such as described in claim 31 in which the lower bearing surfaces of said guides are slightly inclined away from said roller at points below said roller.

34. In an address bearing machine adapted

to operate with stencil cards composed of a relatively thick frame and a thin panel of stencil forming material, the combination of 55 a vertical card magazine, a set of card guides connected with the lower end of said magazine at one side thereof, vertically adjustable fingers located at the bottom of the magazine on its other side for supporting 60 one edge of the card, and a horizontal reciprocating claw adapted to grasp the inner edge of the forward part of each card frame at the bottom of the magazine and force 65 said card into said guides, whereby the proper adjustment of said supporting fingers will allow the forward portion of a warped card to lie in a horizontal position, adapted to be firmly grasped by said claw during its feeding stroke. 70

35. In an addressing machine the combination of a series of stencil cards, an inking mechanism cooperating with said cards successively to stencil the addresses borne by each on the surface of any article superposed on said card while in said inking mechanisms, a magazine adapted to hold a stack of said cards, mechanism for feeding said cards one by one from said magazine to and through said inking mechanism, and a 80 device for returning said cards, after discharge from said inking mechanism, to said magazine, which said device comprises a pair of traveling belts located one over the other above said inking mechanism to form 85 a card conveyor, the upper belt projecting beyond the lower one at the intake end of said conveyor which is located over the discharge side of said inking mechanism, and the discharge end of said belt conveyor 90 being adjustable vertically along an open side of said magazine, together with means for driving said belts and for forcing cards one at a time up against the projecting under surface of said upper belt, whereby 95 each card, after leaving the printing mechanism, may be transferred to said conveyor, carried back between said belts and projected into said magazine at a predetermined point therein.
